COMBINATION WINDOW AND SCREEN

Ralph E. Poulsen, Van Nuys, Calif.

Application February 5, 1954, Serial No. 408,440

1 Claim. (Cl. 160—30)

This invention relates to a roller type window screen for use with a conventional double hung window, one end of the screen being fastened to the window sill and the other end of the screen being wound upon a roller. The roller is carried by a supporting structure which is anchored to the inner (lower) window sash at the lower end thereof so that each time the inner window sash is raised for ventilation purposes, the window screen unrolls and covers the window opening beneath said sash.

One object of the invention is to provide in a roller type screen a combined bracket and casing assembly for rotatably carrying the roller and for anchoring the roller relative to the inner window sash, said bracket and casing assembly including inexpensive and novel construction features.

Another object of the invention is to provide, in a roller type window screen, generally U-shaped brackets which rotatably support the screen roller, said brackets being respectively slidably mounted in and guided by the conventional channels formed in the face of each of the side jambs of the window frame. An upper outwardly projecting leg of each bracket is anchored at a respective end of a U-shaped casing member which is fixed to the window sash and a lower outwardly projecting leg of each bracket has a spring finger anchored thereto for engaging the adjacent margin of the window screen, holding the same in snug contact with one face of the molding strip which forms the outer wall of the jamb channel.

Another object of the invention is to provide novel means for supporting the screen roller relative to the bracket whereby to permit adjustment of the tension spring within the roller without the need of disassembling the roller from its supporting brackets.

Other objects and advantages of the invention will become apparent from the ensuing specifications and the appended drawing in which:

Fig. 1 is a side elevational view of a conventional double-hung window and window frame showing the window screen mounted relative thereto;

Fig. 2 is a sectional view taken on line 2—2 of Fig. 1;

Fig. 3 is a fragmentary sectional view taken on the line 3—3 of Fig. 1;

Fig. 4 is a fragmentary sectional view taken on line 4—4 of Fig. 1;

Fig. 5 is a fragmentary sectional detail view taken on the line 5—5 of Fig. 4; and

Fig. 6 is a fragmentary sectional view taken on the line 6—6 of Fig. 5.

In a conventional double hung window construction the window frame comprises a header 2, a sill 3 and a pair of parallel spaced side jambs 4 and 5. Each jamb is provided with molding strips 6, 7 and 8 which may be integral with or may be separate strips anchored to the inside faces of the jambs. These molding strips extend throughout the length of the jambs, parallel to and spaced from each other whereby to provide a pair of longitudinal channels 9 and 11 in the inner face of each jamb. The channels 9 are opposed to each other and channels 11 are also opposed to each other. The inner

2

window sash 13 has its side margins projecting into channels 9 respectively for sliding movement up and down relative to the jambs and the outer sash 12 is mounted similarly in channels 11. In a conventional double hung window construction the outer window sash 12, when in closed position, covers the upper half of the window opening and the inner sash 13 when in closed position, covers the lower half of the window opening.

The window screen assembly includes a screen 14, the lower margin of which is anchored to the window sill by a bracket, generally referred to by the numeral 15, which extends across the entire length of the window sill from one jamb to the opposite jamb. The bracket 15 may be generally L-shaped in cross section and formed of a pair of angle irons or stampings 16 and 17 nested one within the other and anchoring the lower longitudinal marginal portion of the screen 14 between the two stampings. Several anchors 18 are secured to the window sill as by screws 19 for clamping the bracket 15 to the window sill.

20 The screen is rolled upon a roller 10, carried by inner sash 13.

A roller casing 20 which may be generally U-shaped in cross section and which is open on the underside, has 25 its side wall 21 anchored to the lower marginal portion of the inner window sash as by means of screws 22. The casing extends throughout the length of the window sill and its ends 23 and 24 terminate just short of the outer faces of the molding strips 7 and 8, as best viewed in 30 Fig. 3. The ends of the casing clear the molding strips as the inner window sash and the casing are raised or lowered relative to the window jambs. A pair of U-shaped brackets, generally referred to by the numerals 25 and 26, have respective upper legs 27 which overlap 35 the bridge portion 28 of the casing at opposite ends thereof. Said legs 27 are anchored to the casing as by means of rivets 29. Each of the brackets has a web portion 30 integrally joining its upper and lower legs. The width of the respective brackets, 25, 26 is slightly 40 less than the width of the respective jamb channels 11 so as to permit said brackets to freely slide within said channels whenever the inner window sash is raised or lowered.

The lower leg 32 of each bracket carries a spring finger 33. Each spring finger 33 has a shank 34 which is secured to the inside face of the lower bracket leg as by means of rivets 35. The spring fingers 33 are curved as shown in Fig. 4, and resiliently bear against the respective longitudinal marginal portions of the screen 14, 50 forcing said marginal portions of the screen against the inner faces 37 of the respective molding strips 8 to prevent the entry of insects at the side margins of the screen. It will be noted that as the inner window sash is raised and the screen unwinds from its supporting roller 10, the unwound portion of the screen between the roller and the bracket 15, is maintained in a taut condition by means of the coil spring 39 and the side margins of the screen will rest quite snugly against the inner faces 37 of the molding strip 8 throughout their 55 longitudinal extent even though the spring fingers 33 bear against the margin of the screen at only one point thereof. The side marginal portions of the screen thus bear against the faces of the molding strip throughout the entire height of the unwound portion of the screen. The finger 33, where it bears against the screen, preferably projects outwardly slightly beyond the side edge of the bracket leg, as best viewed in Fig. 4, so that only the finger has contact with the screen.

The roller 10 is tubular and has cylindrical caps 41 and 42 at its respective ends. The cap 41 has a trunnion portion 43 which is rotatably journaled in an opening in the web portion of the bracket 25. A rod 44 is located within the hollow roller and extends throughout a major

portion of the length of the roller. The free end 45 of the rod terminates well within the length of the roller. The other end of the rod 44 has a trunnion portion 46, which terminates with a tip 47 of square section. This squared tip 47 of the rod 44 is normally received in a complementary square aperture 48 in the bridge portion of bracket 26 to normally restrain rotation of the rod relative to the bracket 26. The hollow roller is normally rotatable relative to the rod 44 within the limits permitted by the tension of coil spring 39. One end of the spring 39 is anchored to the roller 10 as at 49 and the other end of the tension spring is anchored to the rod 44 as at 50. The end of the screen which is opposite from the end that is anchored to bracket 15 is anchored to the exterior cylindrical surface of the roller 10 so as to be wound upon the roller or unwound from the roller as the window sash is raised and lowered. During the raising of the window sash as the screen is being unwound from the roller, the rod 44, being stationary, causes the spring 39 to coil, thereby increasing the tension thereof, and when the window sash is lowered, the tension of the spring causes rotation of the roller in the direction to re-wind the screen on the roller.

In the event it is desirable to adjust the tension of the spring 39, it is only necessary to insert a screw driver into the slot 51 and push the rod axially into the roller until the squared stud 47 of the rod clears the inner face 52 of bracket 26. Then the rod may be rotated relative to the roller to change the tension of the spring 39.

The rod 44 has, adjacent trunnion 46, an annular flange 53 which will engage the end 54 of the roller 10 to limit the axial movement of the rod so that the trunnion 46 remains journalled in its bearing—the bearing being the circumferential wall of end cap 42 which defines the aperture therein. The outside diameter of the flange 53, however, is only slightly less than the inside diameter of the inner circumferential wall of the cap 42, thereby assuring continuing alignment of the trunnion 46 relative to the cap aperture.

The flange 53 is of larger diameter than the internal diameter of roller 10, and is received in an annular space defined between the end of roller 10 and the end of member of cap 42, said annular space having an axial dimension which is greater than the thickness of flange 53 by an amount slightly more than the thickness of the web portion 30 of bracket 26, so that the endwise movement of rod 44 will be permitted to a sufficient extent to release stud 47 from its aperture 48 in web member 30.

As a means of closing the gap between sashes when either sash is in an open position, the horizontal lower frame bar of outer sash 12 (or the horizontal upper frame bar of inner sash 13) is preferably provided with a sealing strip 55, attached thereto and extending the full distance between the respective side margins of the opposed window pane of the other sash. Strip 55 is formed to project into engagement with such opposed window pane with a light yielding engagement, and as yieldable to be received between the two horizontal sash bars just mentioned, when both sashes are closed.

I claim:

In combination with a window frame including a sill and spaced opposed jambs each having inner, intermediate and outer spaced parallel vertical molding strips cooperating therewith to define inner and outer adjacent parallel vertical slideways, the ways of the respective jambs being arranged as inner and outer opposed pairs; a lower sash slideable in the inner pair of ways, said sash including a bottom cross frame member; an open bottom roller casing of formed sheet material of inverted channel form horizontally traversing the space between said outer pair of ways with its ends disposed slightly short of said intermediate molding strips, said casing including an inner vertical wall member secured to the outer face of said bottom cross frame member, a top web bent generally horizontally outwardly from the upper extremity of said inner vertical wall member, and an outer wall member bent downwardly from the outer extremity of said top web outwardly of the common plane of the inner transverse faces of the outer molding strips; a pair of brackets, generally of C-configuration, each including a top arm secured to said top web and projecting into a respective outer way, a vertical arm bent downwardly from said top arm and disposed vertically within a respective outer way, and a bottom arm projecting toward the center of the sash from the lower extremity of said outer arm; a spring roller in said casing, its ends projecting into said outer ways and mounted in said vertical bracket arms; a screen anchored to said roller and rolled thereon, the lower end of said screen being anchored to said sill in a plane immediately adjacent said common plane so that said screen makes contact with said inner transverse faces of said outer molding strips at the lower ends thereof; and independent pressure elements of ribbon spring metal each including a flat body portion secured to the bottom arm of a respective bracket and having an integral spring finger projecting upwardly from the outer end of said body portion, curved outwardly in a vertical direction, and yieldingly pressing a respective side marginal portion of said screen against the respective inner transverse face of a respective outer molding strip, said spring roller being operative to maintain the screen stretched flatly in said common plane of said inner transverse faces, with said side marginal portions in contact with said inner transverse faces.
